DUPLEX DOUBLE-ACTING STEAM PUMP

Frank J. Davidson, Philadelphia, Pa.

Application April 20, 1948, Serial No. 22,036

7 Claims. (Cl. 103—49)

1

This invention relates to duplex double action pumps such as used for boiler feed pumps, as an illustration, and wherein reciprocating pistons operate in parallel cylinders, and in particular the invention includes a pump having two parallel cylinders with auxiliary reciprocating cylinders forming pistons therein and with stationary pistons providing combination intake and exhaust valves positioned in the auxiliary cylinders and connected with tubular piston rods at opposite ends of the pump housing. The housing is provided with inlet and discharge connections with automatically operating valves therein and also valve operating pistons connected through the auxiliary cylinders to the valves in the stationary piston.

The purpose of this invention is to provide an improved steam driven duplex double action pump in which the valves are incorporated within the expandable chamber and operated by fluid pressure therein wherein all exterior operating parts and packing glands associated therewith are eliminated.

The usual pump of this type requires considerable maintenance as there are six glands and two fluid pistons that require frequent repacking making it necessary to stock large supplies of costly packing. The metal piston rings wear rapidly and score cylinders requiring periodic renewal and reborning. The piston rods also score and develop shoulders, and the bearings wear and require new bushings. Due to the above and wear in other mechanically operating instrumentalities associated with pumps of this type the efficiency is comparatively low.

With this thought in mind this invention contemplates an improved type of pump wherein the operating instrumentalities are of the floating type wherein the expandable chamber or moving cylinder which functions as a piston floats in a guide cylinder in the fluid being pumped alternately drawing fluid in at one end and forcing it out of the other and with the pressure of the fluid automatically tripping a slide valve within the moving cylinder as the said cylinder approaches the end of the stroke at each end.

The object of this invention is, therefore, to provide a double acting duplex pump wherein substantially all of the operating instrumentalities are incorporated within the pump housing and are positioned in the fluid being pumped.

Another object of the invention is to provide a double acting steam pump in which the pressure of the fluid being pumped actuates the valve mechanism to reverse the direction of the reciprocating element.

2

Another object of the invention is to provide a double acting steam pump in which substantially all packing glands are eliminated.

A further object of the invention is to provide 5 a duplex double acting steam pump wherein substantially all of the operating instrumentalities are incorporated within the housing and positioned in the fluid being pumped which is of a simple and economical construction.

10 With these and other objects and advantages in view the invention embodies a unitary housing having two parallel cylinders therein with auxiliary floating cylinders in the parallel cylinders and stationary pistons with tubular connecting rods in the floating cylinders, and wherein the pistons include slide valves actuated by fluid pressure through small pistons in cylinders at the end of the housing.

Other features and advantages of the invention 15 20 will appear from the following description taken in connection with the drawings, wherein:

Figure 1 is a view showing a vertical longitudinal section through the housing of the pump and on the center of one of the cylinders thereof, with 25 parts broken away.

Figure 2 is a plan view illustrating the connections between the fluid pressure and valve operating cylinders.

Figure 3 is a view showing an end elevation of 30 the housing looking toward the inlet and discharge end.

Figure 4 is a cross section through the housing taken on line 4—4 of Figure 1.

Figure 5 is a horizontal longitudinal section 35 through the auxiliary or floating cylinder, with the other parts omitted.

Figure 6 is a longitudinal section through the 40 stationary piston showing the slide valve therein, and on an enlarged scale.

Figure 7 is a detail showing the exhaust end of the piston.

Figure 8 is a similar detail showing the steam 45 insert in the piston.

Figure 9 is a cross section through the stationary piston taken on line 9—9 of Figure 6, and showing the slide valve therein.

Figure 10 is a detail showing a sectional plan 50 through the steam end of the pump illustrating the valve actuating piston and cylinder on an enlarged scale.

Figure 11 is a detail showing the split ring used at each end of the floating cylinder.

Fig. 12 is a section through the ring shown in 55 Figure 11.

Figure 13 is a longitudinal section through a

check valve adapted to be used in the connections to the valve actuating cylinder.

Figure 14 is a sectional plan through the valve shown in Figure 13.

Figure 15 is a diagrammatic view illustrating the operation of the pump.

Referring now to the drawings wherein like reference characters denote corresponding parts the duplex double acting pump of this invention includes a housing 10 having an inlet connection 11 and an outlet or discharge connection 12, with stationary guide cylinders 13 and 14 in the housing, floating cylinders 15 and 16 in the guide cylinders, stationary pistons 17 and 18 in the floating cylinders, and valve actuating pistons 19 and 20 in cylinders 21 and 22, respectively, at the end of the housing.

In the design shown the housing 10 is provided with supports 23 and 24 with openings 25 and 26 in the upper surface, and the opening 25 is provided with a cover plate 27, with a similar cover plate 28 on the opening 26. The sides are also provided with hand holes 29 and 30 having cover plates 31 and 32 thereon respectively, and in the lower part is a boss 33 having a flange 34 to which the intake connection 11 is secured by bolts 35, while in the upper part of the same end is a boss 36 having a flange 37 to which the discharge connection is secured by bolts 38.

The guide cylinders 13 and 14 are held in a centrally disposed web 39 that divides the housing into chambers 40 and 41, and in the lower part of the housing is a horizontally disposed partition 42 having openings 43 therein which provides a lower low pressure fluid chamber 44, while in the upper part is another horizontally disposed partition 45 having openings 46 therein that provides an upper high pressure fluid chamber 47.

The openings 43 in the partition 42 are provided with rings 48 providing valve seats and valves 49 with stems 50 seat on the rings with the stems slidably held in guides 51 and with the valves resiliently held against the seats by springs 52. The openings 46 in the partition 45 are provided with rings 53 that provide valve seats and valves 54 with stems 55 are positioned on the seats with the stems held in guides 56 and with the valves held by springs 57.

The floating cylinders and stationary pistons of the guide cylinders 13 and 14 are similar and the same reference numerals are applied to both. The floating cylinders 15 and 16 are preferably made of bronze with steel liners 58, and the ends of the cylinders are formed with annular flanges 59 and 60 and recesses 61 and 62 are provided behind the flanges. The exhaust end of each floating cylinder is provided with a head 63 having an annular flange 64 corresponding with the flange 59 and secured thereto by a split ring formed in two sections 65 and 66 with annular recesses 67 and 68 in the inner surfaces thereof that fit snugly over the flanges on the ends of the cylinder and flanges of the cylinder heads. With the split rings freely slidable in the guide or stationary cylinders 13 and 14 the cylinder heads will be locked in the ends of the cylinders. The split rings are provided with dove-tail interlocking joints 69 and 70 as shown in Figure 11. The head 63 is provided with a centrally disposed bore 71 that is slidable over a tubular connecting rod 72 extending from the stationary piston 17, and the bore is provided with a packing gland 73 with a nut 74 at the end thereof.

The steam end of the cylinder 15 is provided

with a head 75 similar to the head 63 and this head is formed with an annular flange 76 that is secured to the flange 60 by a split ring similar to the ring at the other end. The head 75 is provided with a centrally disposed bore 77 through which it is slidably positioned on a tubular connecting rod 78 and the bore is formed with a packing gland 79 having a nut 80 therein. The flange 76 is also provided with openings 83 and 84 through which rods 85 and 86 extend that connect a slide valve 87 in the piston 17 to a piston 19 in the auxiliary cylinder 21. The openings 83 and 84 are provided with packing glands 89 and 90 with nuts 91 and 92 in the ends thereof for holding the packing.

Each side of the housing is provided with openings 93 and 94 which are aligned with the cylinders and the opening 93 is closed by a flange 95 while the opening 94 is closed by a flange 96 on which the cylinder 21 in which the piston 15 is located is mounted by bolts 97. The outer end of the connecting rod 78 is positioned in a socket 98 in a boss 99 on the inner surface of the flange 96 and a key 100 is provided to prevent the rod turning. The socket 98 communicates with a steam supply pipe 101 through a passage 102, as shown in Figure 1. The outer end of the connecting rod 72 is threaded through the flange 95 with a bushing 103 threaded in the flange and provided with a nut 104 having openings for a spanner wrench by which the bushing may be turned. A lock nut 105 is provided on the rod inside of the flange and an exhaust pipe 106 is mounted on the flange through an elbow 107 and a flange 108.

On the inner end of the connecting rod 78 is a core 109 having outlet openings 110 and 111 therein communicating with the interior of the rod 78, and positioned to register with passages 112 and 113 in the piston 17. The core 109 is also provided with inlet openings 114 and 115 that communicate with the interior of the connecting rod 72 through a passage 116 and these openings are positioned to register with exhaust openings 117 and 118 in the piston. The rod 78 is also provided with a flange 119 that fits snugly against the end of the piston and the flange is provided with an opening 120 registering with the passage 113 and an opening 121 that registers with the passage 118.

The slide valve 87 is provided with a port 122 that is positioned to register with the openings 117 and 118 alternately and this valve is actuated by the piston 19 to which it is connected by the rods 85 and 86. The ends of the rods 85 and 86 are formed with shoulders 123 with studs 124 extending from the shoulders and provided with nuts 125 and 126 that secure the ends of the rods in the web 127 of the piston. The piston is provided with a sleeve 128 having inwardly extending edges as shown in Figure 1.

The end of the piston 17 is provided with locating recesses 81 that are positioned to receive pins 82 on the inner surface of the flange 119, as shown in Figure 5, to maintain the ports in the piston in operative positions.

The pistons 19 and 20 are actuated by fluid pressure and as the pressure builds up in the chambers 40 and 41 the pistons move to operate the slide valve 87 in the stationary piston.

The fluid pressure is provided through a series of small connections with a connection 130 having a check valve 131 therein extending from a point 132 in the chamber 41 at the steam end of the cylinder 14 to the point 135 in the end of

cylinder 21, a connection 134 having a check valve 136 therein extending from the chamber 40 in the opposite end of cylinder 14 to a point 133 in the outer end of the cylinder 21 and connected to the housing at the point 137, a connection 138 with a check valve 139 therein from the point 140 in the chamber 40 of the exhaust end of the cylinder 13 to the point 145 at the inner end of the cylinder 22, and a connection 142 with a check valve 143 therein from the point 144 in the chamber 41 in the steam end of the cylinder 13 to the point 141 in the other end of the cylinder 22.

As the floating cylinder 15 travels toward the exhaust end of the housing from the position shown in Figure 1, pressure builds up in the chamber 40 whereby the fluid passes through the connection 138 to the inner end of the cylinder 22 and the piston actuates the slide valve to open the passage 113 to the steam supply and at the same time opens the passage 117 to the exhaust. This causes the floating cylinder 16 to start moving toward the exhaust end of the pump, and as the pressure builds up in the chamber 40 of the cylinder 14 the fluid passes through the connection 134 to the other side of the piston 19 so that the slide valve in the piston 17 is moved in the opposite direction, and by proper timing and synchronization the cylinders will reciprocate continuously with one following the other.

The check valves used in the small control connections are shown in Figures 13 and 14, and it will be understood that any suitable check valve with a control or a diaphragm valve may be used.

The valves shown are formed with a housing 150 having a horizontally disposed web 151 with a valve seat 152 therein, and a valve ring 153 on a floating sleeve 154 is controlled by an adjusting valve 155 carried by a threaded stem 156 in a bushing 157 and held in adjusted position by a lock nut 158 covered by a cap 159. The valve body is provided with an inlet connection 160 and an outlet connection 161, and below the valve 153 is an annular recess 162 with openings 163 extending downward therefrom. As the demand increases the tendency is to close down the check valves to permit longer stroke before the cutoff or reversing action, and as the demand decreases the valve raises to shorten the stroke, thereby pumping less water or fluid.

With the pump at rest the needle check valve 139 is opened whereby pressure from the chamber 40, passing through the connection 138 and entering the cylinder 22 at the point 145 moves the piston 20 toward the opposite end of the cylinder whereby the valve sleeve 87 is moved by the piston to open steam port 110 through which steam passes through opening 112 into the floating cylinder 16 which builds up pressure in chamber 40. This pressure passes through connection 134 to the outer side of cylinder 21, forcing piston 19 inwardly and moving valve sleeve 87 in cylinder 15 so that steam is supplied to the end of floating cylinder 15, forcing cylinder 15 from the position shown in full lines in Figure 15 to that shown in dotted lines.

This builds up pressure in chamber 41 which passes through the connection 142 to the outer end of the cylinder 22 and drives the piston 20 inwardly carrying the valve sleeve 87 into the piston 17 whereby steam is admitted to the end of the cylinder 16 which drives the cylinder from the position shown in dotted lines in Figure 15, to that shown in full lines. By this means pres-

sure builds up in chamber 41 and passes through connection 130 to the inner end of the cylinder 21 driving the piston 19 outwardly and drawing the valve sleeve 87 in the stationary piston so that steam is admitted to the end of the floating cylinder whereby the cylinder travels from the position shown in dotted lines in Figure 15, to that shown in full lines.

This action builds up pressure again in the chamber 40 and fluid under pressure is again carried through the connection 138 to the inner end of the cylinder 22, and the cycle of operation is repeated.

It will be understood that other changes may be made in the design and arrangement of the parts without departing from the spirit of the invention.

What is claimed is:

1. A duplex double acting pump of the reciprocating type comprising a housing having a pair of stationary cylinders therein, a stationary piston in each of said cylinders, tubular intake and exhaust piston rods extending from opposite ends of said pistons, floating cylinders providing movable pistons slidably mounted on the stationary pistons and rods and slidable in the cylinders, slide valves in the stationary pistons opening the inner ends of the floating cylinders alternately to the intake and exhaust rods, and means actuating the said slide valves by the pressure of fluid in the pump, said housing having intake and discharge connections.

2. A double acting reciprocating pump comprising a substantially enclosed housing having a pair of stationary cylinders therein, a stationary piston in each of said cylinders, tubular intake and exhaust piston rods extending from opposite ends of the cylinders and connected to the pistons, floating cylinders providing pistons slidably mounted on the pistons and rods and slidable in the cylinders, slide valves in the stationary pistons opening the inner ends of the floating cylinders alternately to the intake and exhaust rods, and means actuating the said slide valves by fluid pressure of the pump, said housing having intake and discharge connections.

3. A double acting reciprocating pump comprising an enclosed housing with parallel stationary cylinders therein and having intake and discharge connections and a dividing transverse partition, check valves in the said intake and discharge connections, stationary pistons with tubular connecting rods extending from the ends thereof positioned in the cylinders, floating cylinders slidably mounted over the stationary pistons with the ends thereof slidable on the said tubular connecting rods and with the cylinders slidable in the stationary cylinders and providing pump pistons, means supplying steam to the connecting rods at one end of the housing, means exhausting the steam through the connecting rods at the opposite end of the housing, and means controlling the passage of the steam and exhaust in the stationary pistons.

4. A duplex reciprocating pump comprising a housing having parallel stationary cylinders therein with the cylinders supported at the center in a dividing transverse web, said housing having high and low pressure chambers with an outlet connection from the high pressure chamber and an inlet connection to the low pressure chamber, valves between the high and low pressure chambers and inner chambers in which the stationary cylinders are positioned, floating cylinders slidably mounted in said stationary cylinders provid-

floating pistons, stationary pistons in said floating cylinders having tubular rods extending from the ends thereof through the ends of the floating cylinders and secured in the ends of the housing, slide valves in the stationary pistons, and means actuating the slide valves by the fluid pressure of the pump to admit steam alternately to the inner ends of the floating cylinders and at the same time open the opposite ends of said floating cylinders to the exhaust.

5. A pump as described in claim 4, in which the slide valve actuating means includes pistons in auxiliary cylinders and connected to the said slide valves.

6. A pump as described in claim 4, in which the slide valve actuating means includes pistons in auxiliary cylinders and connected to the said slide valves by rods extending through the ends of the floating cylinders.

7. A pump as described in claim 4, in which 10

the slide valve actuating means comprises pistons in auxiliary cylinders and connected to the said slide valves by rods extending through the ends of the floating cylinders and actuated by individual connections with check valves therein from the opposite sides of the pistons in the auxiliary cylinders to the opposite ends of the pump housing.
